(57) **CLAIM**

The ornamental design for a carabiner with male side squeeze buckle, as shown and described.

DESCRIPTION

FIG. 1 is a top plan view of my new design for a carabiner with male side squeeze buckle;

FIG. 2 is a bottom plan view of FIG. 1.

FIG. 3 is a left side elevation view of FIG. 1.

FIG. 4 is a right elevation view of FIG. 1.

FIG. 5 is a front side elevation view of FIG. 1.

FIG. 6 is rear side elevation view of FIG. 1; and,

FIG. 7 is a top perspective view of FIG. 1.

The broken lines in the drawing represent unclaimed environmental material.
